CLAIM

The ornamental design for a table with hidden compartments, as shown and described.

DESCRIPTION

This invention relates to the following applications, filed on the even date herewith, and herein incorporated by reference: U.S. application Ser. No. 29/469,901, entitled Double Shelving System with Hidden Compartments, by Matthew B. Dworman;

U.S. application Ser. No. 29/469,900, entitled Cabinet with Hidden Compartments, by Matthew B. Dworman;

U.S. application Ser. No. 29/469,898, entitled Shelving System with Hidden Compartments, by Matthew B. Dworman; and

U.S. application Ser. No. 29/469,897, entitled Desk with Hidden Compartments, by Matthew B. Dworman.

FIG. 1 is a perspective view of a table of my new design, the table for use as an end table or a nightstand, having hidden compartments, and shown in FIG. 1 with its compartments being in a closed condition;

FIG. 2 is a front elevational view thereof;

FIG. 3 is a side elevational view of the table of FIG. 1 as viewed from its left side, with its right side being a mirror image thereof;

FIG. 4 is a rear elevational view thereof;

FIG. 5 is a top plan view thereof;

FIG. 6 is a bottom plan view thereof;

FIG. 7 is a perspective view of the table of FIG. 1 with its compartments shown in an open condition;

FIG. 8 is a front elevational view of the table of FIG. 7;

FIG. 9 is a side elevational view of the table of FIG. 7 from its left side, with its right side being a mirror image thereof;

FIG. 10 is a top plan view of the table of FIG. 7; and,

FIG. 11 is a bottom plan view of the table of FIG. 7.
